TELEPHONE SYSTEMS

Fernand Pierre Gohorel, Antony, France, assignor to International Standard Electric Corporation, New York, N. Y., a corporation of Delaware

Application December 4, 1952, Serial No. 323,991

Claims priority, application France January 16, 1952

4 Claims. (Cl. 179—22)

This invention relates to automatic telephone systems in which a common or directing member is used to direct the selectors in each hunting or selecting stage.

During the establishing of a call in these stages, various temporary connections must be made in order to direct the selectors, such as connections between the inlet to the selector and director and between the outlets of the selector and the director. These connections can be made by means of relays or finders. In the case of selectors of the crossbar type, certain arrangements which are covered by this invention, make it possible to reduce the size of the connecting members.

A crossbar switch consists of juxtaposed selectors: each selector comprises contacts (equal in number to that of the outlets) all connected to the inlet of the selector and capable, when closed, of connecting said inlet to one of the outlets. The crossbar switch has selection magnets the number of which depends on the number of outlets. By their temporary action these magnets can prepare the closing of a given contact in any of the selectors. Each selector also has a magnet capable of causing and of maintaining the connection.

Normally the corresponding outlets of the individual selectors are multiplied together. In accordance with the invention one of the individual selectors of the switch has its outlets independent of the corresponding outlets of the other individual selectors, and this particular individual selector is used as a member for temporarily connecting a seized individual selector to the director.

One of the features of the invention consists in the use of a member similar to the selectors, placed adjacent to them and capable of temporarily connecting the inlets of the selector to the director, the latter being connected to the inlet of said member and the inlets of said selector being connected to the outlets of said member.

Another feature of the invention is based on a member similar to the selectors and placed adjacent to them, said member being capable of the temporarily connecting one or more circuits associated with the outlets of the selector to the director, said director being connected to the inlet of said member and the outlets of the selector being connected to the outlets of said member.

In certain systems, an idle selector cannot be seized by the preceding selector when the corresponding director is busy. Because of this, this selector cannot be used to route a call. It may be advantageous to provide arrangements that obviate this difficulty.

Another feature of the invention is based on the fact that if a selector is idle and if the corresponding director is busy, the selector can be seized but the call remains recorded on a device common to all the selectors served by the same director until the director is idled, at which time said device causes the seizing of said director and its connection to said selector.

Various other features will become apparent from the following description, given as a non-limitative example, with reference to the attached figures, in which:

2

Fig. 1 shows the parts necessary for an understanding of one form of the invention to be a selector, a director, and the individual selector which acts as a connecting device between the seized selector inlet and said director.

5 Fig. 2 is a variant of the device of Fig. 1 for the case in which the group of selectors associated with the same director cannot receive any further calls as long as one of said selectors is associated with said director.

Fig. 3 shows the parts necessary for an understanding 10 of another form of the invention to be a selector, a director, and the individual selector which acts as a connecting device between the outlet of the seized selector and said director.

In the following description, the relay contacts that are 15 closed when the relay with which they are associated is energized, that is, when it is in the pulled-up position, are denoted by prefixing the letter T to the spring number; and the contacts that are closed when the relay is not energized, that is, when it is in the unoperated position, 20 are denoted by prefixing the letter R to the spring number. In addition, the contact springs associated with a given relay are denoted by affixing one of the numbers from 1 to 9 to the relay reference.

It will be assumed, in all that follows, that the switch 25 used as a selector is a crossbar switch. Each bar is associated with a selection magnet and assumes an active position when this magnet is energized. In that position, said bar prepares the connection of a line to a connecting bar.

30 The selection magnets merely prepare the connection of an individual switch to a line, said connection being caused by an operating magnet peculiar to each individual switch. The connection is held as long as the operating magnet is energized.

35 The method of connecting a crossbar type selector P to a director OC will now be described with reference to Fig. 1. The whole arrangement comprises a selector P with its inlet wires a, b, c, t; its outlet wires a', b', c', t'; its magnets S1, S2, S3 . . . and its connecting magnet 40 VP. Inlet wires a, b, c, t, of P are connected to outlet wires a1, b1, c1, t1 of a particular individual selector X whose outlets are independent from the corresponding outlets of the other selectors.

45 This selector X, which is mounted on the same frame as selector P, provides connection for a sufficient length of time between the inlet of selector P and director OC to permit the positioning of said selector P. Inlet wires a2, b2, c2, t2 and v2 of selector X are connected to director OC. The reference XP has been used to denote 50 the connecting magnet of selector X. Selection magnets S1 and S2 are used by the two selectors X and P.

Normally, the various relays and magnets shown in 55 Fig. 1 are in the unoperated position. The availability of selector P is marked by battery on wire t over the following circuit: wire t, R vp2, resistance Re3, battery. When selector P is seized by the preceding selector P1, ground is applied to wire c, thus completing the following energizing circuit for relay pa: ground on wire c, R vp3, resistance Re1, relay pa, battery. This relay pa, which 60 is common to all the c wires of the selectors capable of being associated with the same director OC, is energized.

Through its contact pa1, it completes the circuit of relay pb, which energizes: ground, T pa1, R xy2, relay pb, battery.

65 Through its front contacts pb1, pb2 and pb4, relay pb prepares the possible energizing circuits of magnets S1, S2 and S3. Through its front contact pb3 it completes the following circuit: ground, T pb3, R pd1, relay pc, battery. Relay pc energizes.

Through its front contact pc1, relay pc completes the energizing circuit of magnet S1 through relay pd. Relay

pd and magnet **S1** energize in series: ground on wire *c*, R *vp3*, T *pb1*, magnet **S1**, T *pc1*, R *pe1*, relay *pd*, battery.

Through its contact *pd1*, relay *pd* opens the energizing circuit of relay *pc*, which, being a slow-acting relay, releases after a certain delay, thus making it possible for contact *s11*, associated with magnet **S1**, to close its contact sufficiently before contact *pc1* opens and breaks the energizing circuit of magnet **S1** and of relay *pd*. At its contact *pd2*, relay *pd* completes the energizing circuit of magnet **XP** after the release of relay *pc*: ground, R *pc3*, T *pd2*, magnet **XP**, battery.

Energized magnet **S1** prepares the connection of selector **X** to the inlet wires *a*, *b*, *c*, *t*, of the calling selector **P**; at its front contacts *s11*, it completes a holding circuit for itself. At its back contact *s11*, it opens the possible energizing circuits of the other magnets **S2** and **S3**, thus preventing the simultaneous operation of several of said magnets.

On operating, magnet **XP** connects selector **X** to outlets *a1*, *b1*, *c1*, *t1* of said selector and, therefore, to inlet wires *a*, *b*, *c*, *t* of calling selector **P**.

At its front contact *xp1*, magnet **XP** completes a holding circuit for itself: battery, magnet **XP**, T *xp1*, R *vp2*, ground on wire *t*. At its back contact *xp2*, it opens the circuit of relay *pb*, which releases.

At its front contact *pb1*, relay *pb* opens the energizing circuit of magnet **S1** and of relay *pd*, both of which release.

Thus, through the operation of magnet **XP**, the inlet wires *a*, *b*, *c*, *t* of calling selector **P** are connected to director **OC** through wires *a1*, *b1*, *c1*, *t1*, *a2*, *b2*, *c2*, *t2*.

Ground is applied to director **OC** over the following circuit: wire *c* of selector **P**, R *vp3*, wires *c1* and *c2* of selector **X**, director **OC**, thus causing the seizure of the director. Said director then closes contact *m1* and relay *pe* is energized.

At its back contact *pe1*, it isolates relay *pd* and prepares, at its front contact *pe1*, an energizing circuit for one of the magnets **S**. At its front contact *pe2* it completes the following energizing circuit for relay *pc*: ground, T *pe2*, R *pd1*, relay *pc*, which energizes, battery.

Director **OC** receives over wires *a2* and *b2* the number of the line or group of lines and causes the operation of a given magnet **S**, which characterizes said line or an idle line of said group. It may be assumed, for example, that the line selected by the director corresponds to magnet **S2**, the following circuit being then completed: contact *gs2* grounded by the director, magnet **S2**, T *pc2*, R *s11*, T *pe1*, resistance *Re2*, battery.

Magnet **S2** energizes and selects the line leaving the selector **P**, since the magnets **S1**, **S2**, **S3** are the select magnets of both **P** and **X**. The director then applies ground to wire *v2*. The following circuit is then completed: ground on the director, wire *v2*, wire *v1* of selector **X**, magnet **VP**, battery. Magnet **VP** energizes.

On operating, magnet **VP** connects the inlet wires *a*, *b*, *c*, *t* of selector **P** to outlet wires *a'*, *b'*, *c'*, *t'*.

At its contact *vp1*, it completes a holding circuit for itself: battery, magnet **VP**, resistance *Re4*, T *vp1*, wire *t*, ground. At its back contact *vp2* it opens the holding circuit of magnet **XP**, which releases. At its contact *vp3* it opens the circuit of relay *pa*, which also releases. At its front contact *vp5* it grounds wire *t* of selector **P** in order to mark a busy condition on the chosen line *a'*, *b'*, *c'*, *t'*, terminating at the following selector **P2**.

On releasing, magnet **XP** breaks the connection between the inlet of selector **P** and director **OC**, which releases.

On releasing, the director opens the circuit of relay *pe*, which releases. It also removes ground from wire *v2*, but magnet **VP**, as already indicated, holds through its contact *vp1*. Through *gs2* ground is removed from the energizing circuit of **S2**, which in turn releases.

Upon releasing, relay *pe* opens the energizing circuit of relay *pc*, which releases.

Magnet **VP** alone remains seized, in order to hold selector **P**.

The case in which several simultaneous calls are received will now be considered. If two selectors **P** are both calling selectors at the same time, preference is given to the first selector controlled by magnet **S1**. The second selector has to wait until the first call has been routed for its magnet to be operated.

A variant of the device shown in Fig. 1 will now be described with reference to Fig. 2. This variant is intended especially for the case where the group of selectors **P** associated with the common director **OC** cannot receive additional calls as long as one of said selectors is associated with said control member.

Availability is marked by the application of battery in the director to wire *t* through contact R *xp3* and contact R *vp3*, indicating to the preceding selector **P1** that associated selector **P** and director **OC** are available. When selector **P1** finds an idle selector **P**, associated with director **OC**, it seizes it and applies battery to wire *a* through back contact *em* and ground to wire *t*; the following circuit is then completed: battery on wire *a*, R *vp2*, left-hand winding of magnet **S1**, R *xp4*, R *xp5*, ground. Magnet **S1** energizes and prepares the connection of selector **X** to calling selector **P**.

At its contacts *s11*, magnet **S1** completes the energizing circuit of magnet **XP**; ground on wire *t* applied by selector **P1**, R *vp3*, T *s11*, magnet **XP**, battery.

Magnet **XP** energizes, and through its front contact *xp3*, completes the following holding circuit for itself: ground, wire *t*, R *vp3*, T *xp3*, resistance *Re6*, magnet **XP**, battery. At its contacts *xp4* and *xp5*, it opens the circuit of magnet **S1**, which releases.

Because of the energization of magnet **XP**, the inlet wires *a*, *b* of selector **P** are thus connected to director **OC** through wires *a1*, *b1* of selector **X** and wires *a2*, *b2*.

The selection control signals are transmitted over wires *a* and *b* to director **OC**. Said director then causes the operation of a given magnet **S**, which characterizes the selected line. Thus, for example, if the selected line is line *a'*, *b'*, *t'*, magnet **S3** is energized over the following circuit: battery, right-hand winding of magnet **S3**, T *gs3*, and ground in director **OC**.

The director then applies ground to wire *v2*, which completes the energizing circuit of magnet **VP**: ground on **OC**, wire *v2*, wire *v1*, magnet **VP**, battery. Magnet **VP** energizes.

When magnet **VP** operates, it connects wires *a*, *b*, *t* of selector **P** to the outlet wires *a'*, *b'*, *t'* of the selected line. When it opens its back contacts *vp2* and *vp3* it disconnects selector **P** from selector **X** and from director **OC**. Because of this, magnet **XP** releases; selector **X** and the director release.

Through its front contact *vp1* it completes a holding circuit: ground applied to wire *t* by selector **P1**, T *vp1*, resistance *Re5*, magnet **VP**, battery. Through its front contact *vp5* it grounds the *t* wire of the chosen selector **P** in order to mark a busy condition on the selected line *a'*, *b'*, *t'*.

As has been indicated, selector **P** cannot be seized unless director **OC** is available. Consequently, as soon as a selector **P** is seized, none of the other selectors **P** controlled by the same director can be seized; selector **X** cannot therefore receive two calls simultaneously and no arrangement is necessary to prevent the simultaneous operation of two **S** magnets.

When selector **P** is available, back contact *vp4* is closed, and when selector **X** is also available, wire *ch1* is grounded; therefore, the wire *ch* peculiar to selector **P** is grounded. Wires *ch* of all the selectors belonging to the same group are multiplied on the same wire *f1*. If there is at least one selector of this group that is available and associated with an available **X** selector, wire *f1* is grounded. On the other hand, if there is no selector in the group that meets these two conditions simultaneous-

ly wire f_1 is isolated. This arrangement makes it possible for selectors located up above to determine whether there is at least one idle line in the group.

In the preceding description, it was assumed that the director could perform its functions by simply being connected to the inlet wires of selector P. It may be necessary in certain cases also to connect the director to all or part of the wires of the selected line. Fig. 3 shows a device whereby it is possible to connect the director to all or part of the selected line.

Selector Y is controlled by selection magnets S'; its outlets are connected to the outlets of selector P; its inlets are connected to director OC.

It will be assumed that the inlet wires a, b, c, t of selector P are connected to director OC through a device C, which may be that shown in Fig. 1 or 2.

Director OC receives the selection control signals over wires a and b and in accordance therewith applies ground to one of the S' selection magnets, S'1, for example, which energizes.

Through its contact $s'11$ (contacts $s'21$ and $s'31$ are connected in parallel with the former), it completes an energizing circuit for magnet YP. This magnet energizes. When the selection or control operation is ended, director OC grounds wire v through contact $g'1$, and through connector C, energizes magnet VP. This magnet VP is energized.

When magnet VP operates, it connects the inlet wires a, b, c, t of selector P to wires a', b', c', t' of the selected line.

Through its contact $vp1$ it establishes a holding circuit: ground on wire t , T $vp1$, resistance $Re7$, magnet VP, battery. Through its contact $vp2$, it disconnects wire t of connector C, causing the release of connector C and of director OC. Through its front contact $vp5$, it grounds selector P for the reasons already set forth. The ground that director OC had applied to magnets S'1 and YP is removed; these magnets release. Selector Y is released.

What I desire to claim and secure by Letters Patent is:

1. A selection system comprising a multi-switch having a plurality of individual selectors, each having an inlet and a plurality of outlets, one of said individual selectors having its outlets connected respectively to the inlets of the other individual selectors, a director connected to the inlet of said one individual selector, means for seizing one of said other individual selectors, means controlled by the seizure of said other selector for causing said one individual selector to connect its inlet with the outlet connected to the seized selector, whereby the seized selector is connected to said director, means controlled by

45
50

said director for preparing said seized individual selector for connecting with a selected outlet, and means also controlled by said director for completing the connection of said seized individual selector with said selected outlet and for releasing said one individual selector to break the connection between said director and the inlet of said seized individual selector.

5 10 15 20 25 30 35 40 45 50

2. A selection system, according to claim 1, in which the director has an additional circuit and in which a second particular one of the individual selectors has its inlet connected to said additional circuit and certain wires of its outlet connected respectively to corresponding outlets of the others of said individual selectors.

3. A selection system, according to claim 1, in which the means controlled by the seizure of the other selector for causing the one individual selector to connect its inlet with the outlet connected to the seized individual selector comprises magnets for respectively preparing said one individual selector for connection to a selected outlet thereof, and relay means controlled by a signal from a preceding selector for energizing the particular one of said magnets for preparing the connection of the inlet of said one individual selector with that of said seized individual selector and for completing the connection so prepared.

2. A selection system comprising a multi-switch having a plurality of individual selectors, each having an inlet and a plurality of outlets, a director, one of said individual selectors having its inlet connected to said director and its outlets respectively multiplied to corresponding outlets of the other individual selectors, means for seizing one of said other individual selectors, means controlled by the seizure of said other individual selector for connecting said director to the inlet of said seized other individual selector, means controlled by said director for preparing said one individual selector for connection to a selected outlet thereof, means controlled by said director for operating said one individual selector, whereby said director is connected to the selected outlet thereof, and means controlled by said director for subsequently operating said seized other individual selector to connect its inlet to its outlet multiplied to said selected outlet and for disconnecting said director from the inlet of said seized other individual selector and for releasing said one individual selector.
